UNITED STATES PATENT OFFICE.

EDWIN G. MUMMERY, OF DETROIT, MICHIGAN.

HYDROCARBON-BURNER.

1,373,144.

Specification of Letters Patent. Patented Mar. 29, 1921.

Application filed April 7, 1919. Serial No. 287,963.

To all whom it may concern:

Be it known that I, EDWIN G. MUMMERY, a citizen of the United States, and residing at Detroit, in the county of Wayne and State 5 of Michigan, have invented a new and Improved Hydrocarbon-Burner, of which the following is a specification.

This invention relates to burners especially adapted for kerosene and other heavy 10 hydrocarbons, and its object is to provide a device of this character which can be made at low cost, which will be odorless when in operation, and which will have maximum efficiency. A further object of this invention 15 is to provide a duplex ring burner, that is, a burner having a plurality of concentric combustion rings, and these rings so proportioned that each shall be of maximum efficiency.

20 This invention consists in a hydrocarbon burner comprising inner and outer chimneys, the inner chimney being in sections, the upper portion of the inner chimney being imperforate, the lower portion of the 25 inner chimney being integral with the vaporizer, the vaporizer being supplied with an annular cover which forms a tight joint with the outer rim of the trough and has an inner ledge to support the outer chimney.

30 It further consists in providing radial flanges at the upper ends of the chimneys extending from each other.

It also consists in providing a cowl for the 35 burner ring, spaced apart from the outer chimney and having an air space around the flange at the upper edge of the outer chimney.

It also consists in providing an inner 40 burner ring consisting of inner and outer perforated chimneys and an annular fuel passage integral preferably with the lower of the sections of the inner chimneys, the vaporizer of the outer ring connecting to the annular fuel passage of the inner ring by 45 means of tubes for the passage of the gasified fuel.

It also consists in the details of construction illustrated in the accompanying drawings and particularly pointed out in the 50 claims.

In the drawings, Figure 1 is a central vertical section of this improved burner. Fig. 2 is a section on the line 2—2 of Fig. 1. Fig. 3 is a central vertical section of a double ring 55 burner embodying my invention. Fig. 4 is a section on the line 4—4 of Fig. 3. Fig. 5

is a partial section shown in Fig. 4. Fig. 6 is a vertical central section of a furnace with a double ring burner in position. Fig. 7 is a section of a single ring burner having slots 60 instead of holes for the passage of air. Fig. 8 is an elevation of a double ring burner thus constructed. Fig. 9 is a section on the line 9—9 of Fig. 8.

Similar reference characters refer to like 65 parts throughout the several views.

Referring to Fig. 1, the vaporizer consists of the bottom 1, outer side 2 and lower part 3 of the inner chimney, and is shown mounted on legs 4 and supplied with liquid fuel 70 through a pipe 5. A lighter wick 6 preferably formed with an asbestos center and metal frame similar to that shown in Fig. 5, will be explained later on.

The inner chimney is shown formed of 75 two parts, the lower part 3 which comprises a portion of the vaporizer, and the upper part 7, but any desired number of upper sections may be used. The adjacent edges of these parts is preferably formed with radial 80 flanges 8, one of the two adjacent flanges being formed with key-hole slots 9 and the other provided with headed pins 10 to secure these flanges and sections together. The upper end of the inner chimney will be closed, 85 a head 12 being shown in Fig. 1. The upper portion of the inner chimney is formed imperforate while the remainder of the inner chimney and the outer chimney 13 are formed with holes 14 to admit air to the 90 combustion space between the chimneys.

The outer chimney rests on and fits within an angular flange 15 on the cover 16 of the vaporizer, the outer flange 17 of this cover fitting tightly around the outer side 2 of the 95 vaporizer. While the liquid fuel may wet the inner side of the part 2 of the vaporizer and the bottom of the cover 16, it does not pass around the flange 15 and the sides of the outer chimney never become wetted by 100 the fuel. The chief cause of the objectionable kerosene odor so often found around burners of this character is thus removed.

A cowl 19 may have fingers or legs 20 that rest on the cover 16 and support this cowl in 105 proper position around the chimney 13, an air space being left around the flange 22 at the upper edge of this outer chimney. This space permits a current of air to pass up to the flame above the burner ring, this air also 110 serving to cool this flange 22, which flanges serve to keep the upper end of the chimney

from warping because of the intense heat of the flame.

While the exact reason is not known, the omission of the perforations 14 at about the 5 upper one-fourth of the inner chimney causes more perfect combustion and a hotter flame than with perforations in this portion of the same chimney.

Instead of holes, the parts 3^a and 7^a of the 10 inner chimney and the outer chimney 13^a shown in Fig. 7 may be formed with narrow slits 24 to permit the passage of air. The details of this burner are otherwise the same as those shown in Fig. 1 and are similarly 15 lettered.

It is quite common to use a group of burners where large amounts of heat are desired, as in heating furnaces. In Fig. 5 I have shown a furnace having outer and inner 20 shells 31 and 32, flues 33 and air pipe 34, and within the combustion chamber a burner of large diameter supplied by the fuel pipe 35. This burner is shown in section in Figs. 3, 4 and 5 and comprises outer and inner 25 burner rings, it being understood that any desired number of concentric burner rings may be employed. I have found that when a single burner ring of large diameter is employed that the shape of the flame is 30 undesirable, as it runs up toward a point, almost in the form of the upper half of an onion. But by using concentric burner rings as shown in Figs. 3, 4 and 9, the individual 35 rings of flame (excepting the inner one) are nearly cylindrical and the combustion is greatly improved.

The vaporizer shown in Fig. 3 is in the same form as that shown in Fig. 1, having a bottom 37 supported by legs 38, outer side 40 39 supporting the cover 40 having an angular flange 42 to support the outer chimney 43 provided at its upper end with a flange 44. The same air space is left between this flange and the upper edge of the cowl 45 45 which again has feet 46 resting on the cover 40. The lower part 47 of the inner chimney of this outer ring supports the upper part 48, and within this chimney is an imperforate cylinder 49 which connects to the upper 50 edge of the inner chimney by means of an imperforate annulus 51. The outer chimney and the major portion of the inner chimney have perforations 50.

A number of pipes 53 extend from the 55 vaporizer to the circular fuel channel 54 of the inner chimney and may be integral with either or both if desired. The perforated outer chimney 55 of the inner ring rests on the outer flange 56 of this fuel channel and 60 the lower part 57 of this inner chimney may be integral with this channel. This lower part 57 and upper part 58 may have flanges 59 removably secured together, as before described, the upper part being closed by 65 means of a head 60. An inner shell or cowl

62 rests on the small pipes 53 and surrounds the inner burner ring, being spaced at its upper end from the flange 63 at the upper end of the outer chimney 55. Small pins 64 may be employed to center this cowl 62 70 with reference to the chimney 55. The upper portion of the inner chimney 58 is again imperforate but the remainder of the inner chimney and the outer chimney 55 will have perforations 65 in the form of 75 holes or slits.

The igniter is preferably in sections, as illustrated in Fig. 5, being built up of an inner ribbon 70 of metal crimped to produce lugs 71 which space it from the inner 80 wall 47 of the vaporizer and having its ends 72 bent to extend into the gas pipes 53, a band 73 of asbestos, and a ribbon 74 of metal preferably gauze. The fingers 75 are preferably struck up from the ribbon 70 and extend through the asbestos 73 and gauze 74.

When this burner is to be used, a small amount of liquid fuel is admitted to the vaporizer through the pipe 35 to saturate 90 the asbestos 73 which is then lighted. This flame soon forms gas which burns between the chimneys 43 and 47 and the burning gas will also travel along the pipes 53 to the space between the chimneys 56 and 57. 95 As more gas is generated the flame will fill the spaces between the two sets of chimneys and extend up above these burner rings.

The chimneys of the outer ring should be spaced about three-eighths of an inch apart 100 and the chimneys of the inner ring somewhat less, the rule seeming to be that this distance should decrease inwardly according to the square root of the distance to the center of the burner. Thus, for an outer 105 burner ring eighteen inches in diameter the distance between chimneys should be three-eighths of an inch, for an inner ring twelve inches in diameter the space should be about three-tenths of an inch wide, for an 110 inner ring nine inches in diameter the space should be about one-fourth of an inch wide, and for an inner ring six inches in diameter the space should be about two-tenths of an inch wide. Actual tests have demonstrated 115 the approximate correctness of these dimensions.

The details and proportions of this burner may all be changed by those skilled in the art to meet the various demands for heating burners of this type without departing from the spirit of my invention as set forth in the following claims.

I claim:

1. In a hydrocarbon burner, the combination of a plurality of concentric burner rings each comprising perforated inner and outer chimneys, an imperforate cowl on the outside of the outer chimney of each burner ring, an imperforate closure for the top 125 130

of the innermost chimney, an imperforate cylinder next within the inner chimney of the outer burner, and an imperforate ring connecting the tops of said last named cylinder and chimney.

2. In a hydrocarbon burner, the combination of a plurality of concentric burner rings each comprising perforated inner and outer chimneys, an imperforate cowl on the outside of the outer chimney of each burner ring, a circular fuel passage at the bottom of each burner ring, pipes connecting said fuel passages, and means to conduct liquid fuel to the outer burner ring.
3. In a hydrocarbon burner, the combination of a plurality of burner rings each comprising perforated inner and outer chimneys, the outer chimneys being perforated throughout their entire height and the inner chimneys being imperforate for about one-fourth of their height at their

upper ends, the remainder of said inner chimneys being perforated, circular fuel passages at the bottoms of said rings, pipes connecting the fuel passages, and means to 25 conduct liquid fuel to the outer burner ring.

4. In a hydrocarbon burner, the combination of a plurality of concentric burner rings each comprising perforated inner and outer chimneys, said chimneys having radial flanges at their upper ends extending in opposite directions in each ring, a cowl on the outside of each outer chimney, said cowls being spaced so as to leave an air 30 passage between the upper ends and the adjacent flanges on the upper ends of the outer chimneys, fuel passages at the bottoms of the burner rings, pipes connecting the fuel passages, and means to conduct liquid 35 fuel to the outer burner ring.

EDWIN G. MUMMERY.
